UNITED STATES PATENT OFFICE.

JAMES NICHOLSON, OF SACRAMENTO, CALIFORNIA.

AUTOMOBILE-SIGNAL.

1,165,117.

Specification of Letters Patent. Patented Dec. 21, 1915.

Application filed April 14, 1914. Serial No. 831,753.

To all whom it may concern:

Be it known that I, JAMES NICHOLSON, a citizen of England, and a resident of Sacramento, in the county of Sacramento and State of California, have invented a new and useful Improvement in Automobile-Signals, of which the following is a specification.

My invention is an improvement in automobile signals, and has for its object to provide a signal for use with vehicles of the character specified arranged to be operated by the chauffeur at will to indicate the intention to turn to one side or the other, and to indicate the direction in which it is intended to turn, wherein a plurality of signals is provided for each mud guard, capable of being moved into and out of operative position, and electrically controlled to be moved into operative position and to be held in such position, and wherein spring operated mechanism is provided for automatically releasing the signal after the lapse of a predetermined length of time.

In the drawings:—Figure 1 is a front view of an automobile provided with the improved signal, Fig. 2 is an enlarged section on the line 2—2 of Fig. 1, looking in the direction of the arrows and with the wiring shown diagrammatically, Fig. 3 is a section on the line 3—3 of Fig. 2, looking in the direction of the arrows, and showing the parts in one position, Fig. 4 is a similar view showing the parts in another position, and Fig. 5 is a front view of the spring operated mechanism for releasing the signal.

The present embodiment of the invention is shown in connection with an automobile 1 of any desired type, the signal mechanism being contained in a box or casing 2, which is built into or arranged upon each of the mud guards 3 of the vehicle. Each of the casings is provided with an opening in one face, and a plurality of sheets 4 of transparent material as for instance, glass, is arranged at the opening for closing the same as shown in Figs. 2, 3 and 4. It will be noted that the opening is divided by a vertical bar 5, into two portions, and a sheet 4 is arranged between each end of the casing and the bar. A plurality of signal mechanisms is arranged in each casing, the said signals being similar and similarly arranged and operated and released in precisely the same manner.

The signal is in the form of a frame or

plate 6, hinged at 7 behind the adjacent sheet 4 of transparent material and at the bottom thereof, to swing into a position behind the sheet and approximately parallel therewith as shown in Fig. 2, or into a horizontal position as shown in Fig. 4. The upper or outer face of each of the plates 6 is provided with a signal indication, as for instance, an arrow pointing and a legend as for instance, the legend "Turn." The arrow points in the direction toward which it is intended to turn. It is obvious that any other data might be placed upon the plate if desired, and the signals of each casing are oppositely arranged, preferably the arrow of each plate pointing toward the adjacent end of the casing.

A pair of magnets 8 is arranged adjacent to each signal, and a lever 9 is pivoted intermediate its ends as indicated at 10, adjacent to each pair of magnets. Each of the levers is beneath the end of the adjacent signal and that portion of each lever in front of the pivotal connection is curved and arranged with its concave face upwardly. The free forward end of the lever is in position to engage and lift the signal into the position of Fig. 3, when the opposite end of the lever is depressed in a manner to be described. An arm 11 is pivoted to the rear wall of the casing adjacent to each pair of magnets as indicated at 12, and the said arm extends forwardly above the cores of the magnets, and is provided in front of the magnets with a downwardly extending angular portion 13. At the cores of the magnets, the arm 11 is widened as indicated at 14 to extend above the cores of both magnets, and the arm is the armature of the magnets. The lower end of the angular portion 13 normally engages the rear end of the adjacent lever 9, and the said rear end of the lever is provided with an angular lug or stop 15, behind the said angular portion of the arm. The arrangement is such that when the magnets are energized to attract the armature the portion 13 of the arm will be moved downwardly to depress the rear end of lever 9 to swing the lever to cause it to lift the signal into the approximate vertical position of Fig. 3.

Each of the signals is held in lifted or operative position by means of a resilient latch plate 16. Each of the latch plates has one end secured to a frame to be presently described as indicated at 17, and the other

end of the latch plate is provided with a catch 18, for engaging over the upper edge of the signal plate 6, to hold the plate in operative or approximately vertical position.

An illuminating means, an incandescent electric light 19, in the present instance, is arranged adjacent to each signal in position to illuminate the signal when the signal is lifted, and the signal indications of each plate are preferably made by perforating the plate on the lines that outline the indications. The arrangement of the indications is such that when the signal is in the position of Fig. 3, the illumination within the casing will make the signal indications visible. It is obvious that any desired arrangement that would permit this function might be used. The wiring of the signals is shown in Fig. 2, for one casing, and it will be obvious that were four signal casings used, the arrangement would be the same, the corresponding signal operating magnets of the casing being arranged in the same manner as for the two shown in Fig. 2, so that by operating a signal switch the corresponding signals of all of the casings will be actuated.

As shown in Fig. 2, the magnets 8 of the signal at the left of the casing are interposed in an electric circuit, consisting of the lead wires 20 and 21. A source of electrical energy as for instance, a battery 22, is interposed in the circuit, as is also a switch 23, of any desired character, as for instance, a push button or the like.

The magnets of the signal at the right of the casing are interposed in a circuit consisting of the lead wires 20 and 21^a, and a battery 22^a, and a switch 23^a are interposed in the circuit. The switches 23 and 23^a are normally opened and it will be obvious that when either switch is closed the magnets pertaining thereto will be energized to swing the portion 13 of the adjacent arm 11 downwardly to cause the said portion 13 to swing the lever 9 in a direction to lift the signal into the position of Fig. 3, when it is held by the catch 18 of the latch plate 16.

A spring motor is provided for releasing the latch plate 16 to permit the signal to fall of its own weight into inoperative position. The said motor comprises front and rear cheek plates 24 and 24^a, connected together by bolts and nuts 25, and held in spaced relation by arbors 26 on the bolts.

The inner end of each latch plate 16 is connected to a plate 27, which is secured to the arbors of the uppermost bolts 25 of the adjacent frame. A shaft 28 is journaled between the cheek plates and one end of the shaft extends outside of the casing 2, and is polygonal as shown at 29, to receive a key indicated at 30, in dotted lines, to turn the shaft to wind the spring 31, connected there-

with. One end of the spring 31 is connected to the shaft and the other end is connected to the arbor 26 of the adjacent bolt 25. A gear wheel 32 is secured to the shaft, and the said wheel meshes with a pinion 33 on a second shaft 34, journaled between the cheek plates and extending beyond the rear cheek plate, as shown in Fig. 3, for a purpose to be presently described. The shaft 34 is provided with a gear wheel 35, which meshes with a pinion 36 on a third shaft 37. The shaft 37 is provided with a gear wheel 38, which meshes with a pinion 39 on a shaft 40, and the shaft 40 is provided with a gear wheel 41, which meshes with a pinion 42 on a fan or governor shaft 43.

The shaft 43 is provided with oppositely extending wings or vanes 44, constituting a fan or governor, for regulating the speed of the motor. A resilient arm 45 is secured to the bottom of the casing as indicated at 46, adjacent to each signal, and in position to be engaged by the signal, when the signal is in inoperative or horizontal position, to swing the upper end of the arm rearwardly. The upper end of each of the resilient arms is provided with an angular lug 47, and the said lug is so arranged that when the signal plate strikes the arm 45, the lug 47 of the arm will be moved into the path of movement of the wings or vanes 44, and will engage one of the said wings or vanes to check the movement of the governor shaft 43 and to stop the operation of the motor. When the signal is swung upwardly as indicated in Fig. 3, the resilience of the arm will move it forwardly to disengage the lug from the governor shaft. A cam 48 is secured to the front end of the shaft 34, and the cam is adapted to engage a vertically movable rod 49, which is mounted in bearing arms 50, extending forwardly from the front cheek plate 24. The rod 49 has its lower end in contact with the cam, while the upper end is provided with a head 51, which engages the adjacent latch plate 16. It will be obvious that when the high part of the cam engages the lower end of the rod, the rod will be moved upwardly and the head by its engagement with the latch plate will lift the same to release the catch 18 from the adjacent signal to permit the said signal to drop into inoperative or horizontal position.

The operation of the device, as a whole, is as follows:—When the chauffeur desires to turn in either direction, he will close the switch of the signals at that side of the vehicle. As for instance, supposing that the driver intends to turn to the left of Fig. 1, he will close the switch 23. When the switch is closed, the magnets 8 at that end of the casing will be energized to move the arm 11 downwardly and to swing the lever 9 in a direction to lift the signal plate at that

end of the casing. The plates are light in weight, and when lifted the engagement of the catch 18 of the adjacent latch plate will hold the signal in operative position. The 5 lifting of the signal plate will release the adjacent arm 45, and of its own resiliency the said arm will swing out as indicated in connection with the remote signal of Fig. 3. The forward movement of the arm will 10 withdraw the lug 47 thereof from its engagement with the governor and the spring will begin to drive the train of gears, thus rotating the shaft 34, while the governor makes the movement of the train of gears 15 uniform. As the cam rotates the rod 49 will be lifted and the latch plate will be lifted to release the signal, which of its own weight will fall into the inoperative position, as shown in Fig. 4. It is obvious 20 that the arrangement may be such that the signals will be released at any desired time, as for instance, five seconds, ten seconds, or the like. As soon as the signal is released, it will fall into the position of Figs. 25 3 and 4, swinging the resilient arm rearwardly into engagement with the fan or governor, thus immediately checking the movement of the motor. As soon as the signals are in inoperative position, the 30 motors pertaining thereto are motionless, and the lifting of the signals to operative position starts the motor belonging thereto.

Preferably the signal casing 2 is shaped to fit the mud guard, as indicated in Fig. 35 1, and the signals may be arranged at the rear of the vehicle as well as the front or they may be used at either end and omitted at the other.

The only attention required on the part 40 of the chauffeur is the initial closing of the switch. After the switch has been closed, the remainder of the operation is automatic. When the signals are at the front end of the vehicle, the drivers of approaching vehicles are warned at once as to the intention 45 of the driver of the first vehicle. When arranged at the rear of the vehicle, drivers of following vehicles will be likewise warned. Preferably the signals are in the form of 50 frames, each having a plate, every part of which is covered with a material of opaque character, except the indications. Preferably the illuminating means for the signals is so arranged that the movement of the signal into and out of operative position will 55 close an open circuit in which the illuminating means is interposed to control the said means. When the signal moves into operative position, it operates the switch to close 60 the circuit while when it moves into inoperative position, it actuates the switch to open the circuit.

I claim:

1. A device of the character specified, 65 comprising a signal casing adapted to fit

upon the mud guard of a motor vehicle and having a plurality of openings in its front wall, each opening being covered by a sheet of transparent material, a signal at each opening and hinged to the casing at the bottom of the opening for swinging movement into a position approximately parallel with the sheet or into approximately horizontal position, a lever pivoted to the casing adjacent to each signal and having one end in 70 position to engage the signal and move it into approximately vertical position when the other end of the lever is depressed, an arm hinged to the rear wall of the casing and having a depending portion engaging 75 the rear end of the lever, a pair of magnets arranged beneath each arm near the front end thereof, the armature of the magnets being connected with the arm, an open electrical circuit for each signal in which the 80 magnets adjacent to the signal are interposed, means for closing the circuit, a resilient latch plate supported adjacent to each signal and having a catch for engaging the signal to hold it in operative position, a 85 spring operated motor for each signal, a governor for controlling each motor, a vertically movable rod adjacent to each latch plate and having its upper end engaging the plate to move the plate when the rod is lifted, a 90 cam shaft driven by the motor, a cam on the shaft with which the lower end of the rod contacts for operating the rod, and means operated by the return of each signal to inoperative position for stopping the 100 motor, said means comprising a resilient arm secured to the bottom of the casing adjacent to the signal and adapted to be engaged by the signal as it moves to inoperative position to move the arm toward the 105 motor, each arm having a stop for engaging the governor to check the motor.

2. A device of the character specified, comprising a signal casing adapted to fit upon the mud guard of a motor vehicle, 110 and having a plurality of openings in its front wall, each opening being covered by a sheet of transparent material, a signal at each opening and hinged to the casing at the bottom of the opening for swinging 115 movement into a position approximately parallel with the sheet or into approximately horizontal position, a lever pivoted to the casing adjacent to each signal and having one end in position to engage the 120 signal and move it into approximately vertical position when the other end of the lever is depressed, an arm hinged to the rear wall of the casing and having a depending portion engaging the rear end of 125 the lever, a pair of magnets arranged beneath each arm near the front end thereof, the armature of the magnets being connected with the arm, an open electrical circuit for each signal in which the magnets adjacent 130

to the signal are interposed, means for closing the circuit, a resilient latch plate supported adjacent to each signal and having a catch for engaging the signal to hold it in operative position, a spring operated motor for each signal, a governor for controlling each motor, a vertically movable rod adjacent to each latch plate and having its upper end engaging the plate to move the plate when the rod is lifted, a cam shaft driven by the motor, a cam on the shaft in which the lower end of the rod contacts for operating the rod, and means operated by the return of each signal to inoperative position for stopping the motor.

3. A device of the character specified, comprising a signal casing adapted to fit upon the mud guard of a motor vehicle, and having a plurality of openings in its front wall, each opening being covered by a sheet of transparent material, a signal at each opening and hinged to the casing at the bottom of the opening for swinging movement into a position approximately parallel with the sheet or into approximately horizontal position, a lever pivoted to the casing adjacent to each signal and having one end in position to engage the signal and move it into approximately vertical position when the other end of the lever is depressed, an arm hinged to the rear wall of the casing and having a depending portion engaging the rear end of the lever, a pair of magnets arranged beneath each arm near the front end thereof, the armature of the magnets being connected with the arm, an open electrical circuit for each signal in which the magnets adjacent to the signal are interposed, means for closing the circuit, a resilient latch plate supported adjacent to each signal and having a catch for engaging the signal to hold it in operative position, a spring motor in the casing for each signal, means operated by the movement of the motor for releasing the adjacent latch plate, and means operated by the movement of the signal into and out of inoperative position for stopping and releasing the motor.

4. A device of the character specified, comprising a signal casing adapted to fit upon the mud guard of a motor vehicle, and having a plurality of openings in its front wall, each opening being covered by a sheet of transparent material, a signal at each opening and hinged to the casing at the bottom of the opening for swinging movement into a position approximately parallel with the sheet or into approximately horizontal position, a lever pivoted to the casing adjacent to each signal and having one end in position to engage the signal and move it into approximately vertical position when the other end of the lever is depressed, an arm hinged to the rear wall of the casing and having a depending portion engaging the rear end of

the lever, a pair of magnets arranged beneath each arm near the front end thereof, the armature of the magnets being connected with the arm, an open electrical circuit for each signal in which the magnets adjacent to the signal are interposed, means for closing the circuit, a resilient latch plate supported adjacent to each signal and having a catch for engaging the signal to hold it in operative position, a spring motor within the casing for each signal, means operated by the movement of the motor for releasing the adjacent latch plate, and means operated by the movement of the signal into and out of inoperative position for stopping and releasing the motor.

5. A device of the character specified, comprising a casing having a transparent front wall, a signal hinged to the casing adjacent to the opening for swinging movement into operative or approximately vertical position or into inoperative or approximately horizontal position, means for swinging the signal into vertical position, a magnet for operating the said swinging means, an open electrical circuit in which the magnet is interposed, means for closing the circuit at will, a resilient latch plate for holding the signal in operative position, a spring operated motor in the casing, means operated by the movement of the motor for releasing the latch plate, and means operated by the movement of the signal into and out of inoperative position for checking and releasing the motor, said signal being translucent, a source of light within the casing, and means operated by the movement of the signal into and out of operative position for controlling the source.

6. A device of the character specified, comprising a casing having a transparent front wall, a signal hinged to the casing adjacent to the opening for swinging movement into operative or approximately vertical position or into inoperative or approximately horizontal position, means for swinging the signal into vertical position, a magnet for operating the said swinging means, an open electrical circuit in which the magnet is interposed, means for closing the circuit at will, a resilient latch plate for holding the signal in operative position, a spring operated motor in the casing, means operated by the movement of the motor for releasing the latch plate, means operated by the movement of the signal into and out of the inoperative position for checking and releasing the motor, said signal being translucent, and means within the casing for illuminating the same.

7. A device of the character specified, comprising a casing having a transparent front wall, a signal hinged to the casing adjacent to the opening for swinging movement into operative or approximately vertical position or into inoperative or approxi-

end of the casing. The plates are light in weight, and when lifted the engagement of the catch 18 of the adjacent latch plate will hold the signal in operative position. The lifting of the signal plate will release the adjacent arm 45, and of its own resiliency the said arm will swing out as indicated in connection with the remote signal of Fig. 3. The forward movement of the arm will withdraw the lug 47 thereof from its engagement with the governor and the spring will begin to drive the train of gears, thus rotating the shaft 34, while the governor makes the movement of the train of gears uniform. As the cam rotates the rod 49 will be lifted and the latch plate will be lifted to release the signal, which of its own weight will fall into the inoperative position, as shown in Fig. 4. It is obvious that the arrangement may be such that the signals will be released at any desired time, as for instance, five seconds, ten seconds, or the like. As soon as the signal is released, it will fall into the position of Figs. 3 and 4, swinging the resilient arm rearwardly into engagement with the fan or governor, thus immediately checking the movement of the motor. As soon as the signals are in inoperative position, the motors pertaining thereto are motionless, and the lifting of the signals to operative position starts the motor belonging thereto.

Preferably the signal casing 2 is shaped to fit the mud guard, as indicated in Fig. 1, and the signals may be arranged at the rear of the vehicle as well as the front or they may be used at either end and omitted at the other.

The only attention required on the part of the chauffeur is the initial closing of the switch. After the switch has been closed, the remainder of the operation is automatic. When the signals are at the front end of the vehicle, the drivers of approaching vehicles are warned at once as to the intention of the driver of the first vehicle. When arranged at the rear of the vehicle, drivers of following vehicles will be likewise warned. Preferably the signals are in the form of frames, each having a plate, every part of which is covered with a material of opaque character, except the indications. Preferably the illuminating means for the signals is so arranged that the movement of the signal into and out of operative position will close an open circuit in which the illuminating means is interposed to control the said means. When the signal moves into operative position, it operates the switch to close the circuit while when it moves into inoperative position, it actuates the switch to open the circuit.

I claim:

1. A device of the character specified, comprising a signal casing adapted to fit

upon the mud guard of a motor vehicle and having a plurality of openings in its front wall, each opening being covered by a sheet of transparent material, a signal at each opening and hinged to the casing at the bottom of the opening for swinging movement into a position approximately parallel with the sheet or into approximately horizontal position, a lever pivoted to the casing adjacent to each signal and having one end in position to engage the signal and move it into approximately vertical position when the other end of the lever is depressed, an arm hinged to the rear wall of the casing and having a depending portion engaging the rear end of the lever, a pair of magnets arranged beneath each arm near the front end thereof, the armature of the magnets being connected with the arm, an open electrical circuit for each signal in which the magnets adjacent to the signal are interposed, means for closing the circuit, a resilient latch plate supported adjacent to each signal and having a catch for engaging the signal to hold it in operative position, a spring operated motor for each signal, a governor for controlling each motor, a vertically movable rod adjacent to each latch plate and having its upper end engaging the plate to move the plate when the rod is lifted, a cam shaft driven by the motor, a cam on the shaft with which the lower end of the rod contacts for operating the rod, and means operated by the return of each signal to inoperative position for stopping the motor, said means comprising a resilient arm secured to the bottom of the casing adjacent to the signal and adapted to be engaged by the signal as it moves to inoperative position to move the arm toward the motor, each arm having a stop for engaging the governor to check the motor.

2. A device of the character specified, comprising a signal casing adapted to fit upon the mud guard of a motor vehicle, and having a plurality of openings in its front wall, each opening being covered by a sheet of transparent material, a signal at each opening and hinged to the casing at the bottom of the opening for swinging movement into a position approximately parallel with the sheet or into approximately horizontal position, a lever pivoted to the casing adjacent to each signal and having one end in position to engage the signal and move it into approximately vertical position when the other end of the lever is depressed, an arm hinged to the rear wall of the casing and having a depending portion engaging the rear end of the lever, a pair of magnets arranged beneath each arm near the front end thereof, the armature of the magnets being connected with the arm, an open electrical circuit for each signal in which the magnets adjacent to the signal are interposed, means for closing the circuit, a resilient arm secured to the bottom of the casing adjacent to the signal and adapted to be engaged by the signal as it moves to inoperative position to move the arm toward the motor, each arm having a stop for engaging the governor to check the motor.

- to the signal are interposed, means for closing the circuit, a resilient latch plate supported adjacent to each signal and having a catch for engaging the signal to hold it in operative position, a spring operated motor for each signal, a governor for controlling each motor, a vertically movable rod adjacent to each latch plate and having its upper end engaging the plate to move the plate when the rod is lifted, a cam shaft driven by the motor, a cam on the shaft in which the lower end of the rod contacts for operating the rod, and means operated by the return of each signal to inoperative position for stopping the motor. 3. A device of the character specified, comprising a signal casing adapted to fit upon the mud guard of a motor vehicle, and having a plurality of openings in its front wall, each opening being covered by a sheet of transparent material, a signal at each opening and hinged to the casing at the bottom of the opening for swinging movement into a position approximately parallel with the sheet or into approximately horizontal position, a lever pivoted to the casing adjacent to each signal and having one end in position to engage the signal and move it into approximately vertical position when the other end of the lever is depressed, an arm hinged to the rear wall of the casing and having a depending portion engaging the rear end of the lever, a pair of magnets arranged beneath each arm near the front end thereof, the armature of the magnets being connected with the arm, an open electrical circuit for each signal in which the magnets adjacent to the signal are interposed, means for closing the circuit, a resilient latch plate supported adjacent to each signal and having a catch for engaging the signal to hold it in operative position, a spring motor within the casing for each signal, means operated by the movement of the motor for releasing the adjacent latch plate, and means operated by the movement of the signal into and out of inoperative position for stopping and releasing the motor. 5. A device of the character specified, comprising a casing having a transparent front wall, a signal hinged to the casing adjacent to the opening for swinging movement into operative or approximately vertical position or into inoperative or approximately horizontal position, means for swinging the signal into vertical position, a magnet for operating the said swinging means, an open electrical circuit in which the magnet is interposed, means for closing the circuit at will, a resilient latch plate for holding the signal in operative position, a spring operated motor in the casing, means operated by the movement of the motor for releasing the latch plate, and means operated by the movement of the signal into and out of inoperative position for checking and releasing the motor, said signal being translucent, a source of light within the casing, and means operated by the movement of the signal into and out of operative position for controlling the source. 6. A device of the character specified, comprising a casing having a transparent front wall, a signal hinged to the casing adjacent to the opening for swinging movement into operative or approximately vertical position or into inoperative or approximately horizontal position, means for swinging the signal into vertical position, a magnet for operating the said swinging means, an open electrical circuit in which the magnet is interposed, means for closing the circuit at will, a resilient latch plate for holding the signal in operative position, a spring operated motor in the casing, means operated by the movement of the motor for releasing the latch plate, means operated by the movement of the signal into and out of the inoperative position for checking and releasing the motor, said signal being translucent, and means within the casing for illuminating the same. 7. A device of the character specified, comprising a casing having a transparent front wall, a signal hinged to the casing adjacent to the opening for swinging movement into operative or approximately vertical position or into inoperative or approxi-

mately horizontal position, means for swing-
ing the signal into vertical position, a mag-
net for operating the said swinging means,
an open electrical circuit in which the mag-
net is interposed, means for closing the cir-
cuit at will, a resilient latch plate for hold-
ing the signal in operative position, a spring
operated motor in the casing, means oper-
ated by the movement of the motor for re-
leasing the latch plate, and means operated
by the movement of the signal into and out
of inoperative position for checking and re-
leasing the motor.

8. A device of the character specified,
comprising a casing having an opening in
its front wall, a signal hinged to the casing
at the bottom of the opening and mounted
to swing into approximately vertical or op-
erative position or into approximately hori-
zontal or inoperative position, means oper-
able from the distance for swinging the sig-
nal into operative position, a resilient latch
plate for holding the signal in operative po-
sition, a guided rod engaging the latch plate
for releasing the same when the rod is
moved vertically upward, a spring operated
motor having means for engaging and mov-
ing the rod, and means operated by the
movement of the signal into operative and
inoperative position for starting and check-
ing the movement of the motor.

9. A device of the character specified,
comprising a casing having an opening in
its front wall, a signal hinged to the casing
at the bottom of the opening and mounted
to swing into approximately vertical or op-
erative position or into approximately hori-
zontal or inoperative position, means oper-
able from a distance for swinging the signal
into operative position, releasable means for
holding the signal in operative position, a
normally active spring motor for releasing

the holding means, and means operated by
the movement of the signal into and out of
inoperative position for stopping and releas-
ing the motor.

10. A device of the character specified,
comprising a signal hinged at its bottom to
swing into operative or approximately ver-
tical position, or into inoperative or ap-
proximately horizontal position, releasable
means for holding the signal in operative
position, a normally operative spring motor
for releasing the holding means, and means
operated by the movement of the signal into
and out of inoperative position for
stopping and releasing the motor.

11. A device of the character specified,
comprising a signal mounted to swing into
and out of operative position, electrically
controlled means for swinging the signal
into operative position, releasable means for
holding the signal in operative position, nor-
mally active means for releasing the hold-
ing means after a predetermined interval
to permit the signal to return to inoperative
position, and means controlled by the move-
ment of the signal into and out of inopera-
tive position for controlling the said releas-
ing means.

12. A device of the character specified,
comprising a signal mounted to swing into
and out of operative position, means for
swinging the signal into operative position,
releasable means for holding the signal in
operative position, normally active means
for releasing the holding means, and means
operated by the movement of the signal into
and out of operative position for con-
trolling the said releasing means.
